GEORGE W. WOOD, OF RICHMOND, INDIANA.

Letters Patent No. 65,984, dated June 18, 1867.

INKING APPARATUS FOR PRINTING-PRESSES.

The Schedule referred to in these Letters Patent, and making part of the same.

TO ALL WHOM IT MAY CONCERN:

Be it known that I, GEORGE W. WOOD, of Richmond, in the county of Wayne, and State of Indiana, have invented a new and useful Improvement in Inking Apparatus for Printing in Several Colors; and I do hereby declare that the following is a full, clear, and exact description of the same, reference being had to the annexed drawings, making part of this specification, in which—

Figure 1 is a perspective view.

Figure 2 is a side elevation partly in section.

Figure 3 is a vertical transverse section.

Figure 4 is a section of a part of the apparatus.

Figure 5 is a longitudinal vertical section in part.

The same letters are employed in all the figures in the indication of identical parts.

The object of this invention is to provide for the transfer of ink from a series of continuous fountains, and to dispose the several colors properly distributed upon a roller in bands adjusted to the form to be employed, from which they are to be transferred to the lines of type in the form. I have not shown the inking-fountains, nor the rollers for effecting distribution. These parts may be made according to any of the various systems in use. My invention consists in the use of a series of adjustable sector-plates, arranged in sets upon a common shaft, each set being employed to transfer one color from the fountain to the roller which applies the ink to the types; and I have shown only such parts of the mechanism as include the features claimed as new, arranged for printing in three colors.

The following description will enable a person skilled in the art to construct and apply my improvements to use.

A is the frame, having at each end A A' bearings for the shaft B, which may be driven by any convenient power. At the ends of the shaft, inside of the frame, the cam-wheels C C' are placed. These wheels are, as I prefer to construct them, screwed on to the shaft for more convenient removal, for the purpose of adjusting the inking-sectors. These wheels have three grooves cut in their periphery, in the bottoms of which are adjustably placed strips of India rubber D D' D'', attached by set-screws D³. These strips extend respectively around two-thirds of the circumference of the circle, and act respectively as cams to control the action of the wheels R R' R'', which run respectively in the grooves, as will be more fully explained hereafter. E E' E'' are sector-plates, the form of which is clearly shown in fig. 3. The face of these plates forms an arc of a little less than a third of a circle, and their width varies according to the size of the particular type to which it is designed to communicate the color. These sector-plates are arranged upon the shaft in three sets, separated by the rings G, and when properly arranged in reference to the work, they are secured in position by the nuts G' and the feather F on the shaft B, holding them all in position and preventing their turning upon the shaft and changing their relation to one another. H H' H'' are soft composition rollers, to which the ink is applied from corresponding fountains, each roller receiving its proper color, and transferring it to the proper set of sector-plates. This transfer is effected by means of the following mechanism: On the shaft of the rollers H H' H'', at each end, are placed wheels K K' K'', the rims of which run respectively in the grooves of the wheels C C'. These shafts are made to run in boxes I I' I'', which slide horizontally in slots in the frame A. The ends of these boxes are attached to spiral springs L L' L'', by which they are drawn to the centre of the apparatus. These cams D D' D'' in the wheels C C' being respectively arranged opposite to one another, and on the same arc, the two ends of the rollers H H' H'' will be kept in the same line, and always parallel to the faces of the sector-plates. When the cams D D' D'' are traversing respectively against the wheels K K' K'', they will push the rollers H H' H'' away from the sector-plates, and bring them in contact with the fountains or intermediate feed-rollers, from which they receive their respective colors. At all other times, in the revolution of the wheels C C', these rollers will be in contact with the face of the sector-plates, to which they will transfer their color. These cams must be so adjusted that each set of sector-plates will successively receive its proper color. The sector-plates, in revolving, will transfer their colors successively to the soft type-rollers M M' in bands corresponding with the several lines of types in the form to be printed.

I have shown an apparatus for printing in three colors; the number may be increased, modifying the parts accordingly.

What I claim as my invention, and desire to secure by Letters Patent, is—

1. Sector-plates E E¹ E², adjustably arranged in sets, for transferring the ink from the fountains, and disposing the colors in bands upon the type-rollers.

2. The combination upon one shaft of the sector-plates and cam-wheels C C'.

3. The combination of the ink-fountain rollers, a corresponding number of sets of sector-plates, and a type-inking or other receiving roller or rollers.

In testimony whereof I have signed my name to this specification in the presence of two subscribing witnesses,

GEO. W. WOOD.
